UNITED STATES PATENT OFFICE.

VINCENZO MASSACESE, OF NEW YORK, N. Y.

FURNITURE.

1,232,357.

Specification of Letters Patent. Patented July 3, 1917.

Application filed November 17, 1915. Serial No. 61,975.

To all whom it may concern:

Be it known that I, VINCENZO MASSACESE, a subject of the King of Italy, residing at New York, in the county of New York and 5 State of New York, have invented new and useful Improvements in Furniture, of which the following is a specification.

The present invention relates to improvements in furniture, an object being to provide an article of this class which may be easily and quickly converted from a couch 10 or single bed to a davenport or from a davenport to a double bed.

A further object of the invention is to 15 provide an article of this class which shall embody the desirable features of simplicity, cheapness and thorough efficiency.

With the above and other objects in view, the improvement resides in the construction, 20 combination and arrangement of parts set forth in the following specification and falling within the scope of the appended claims.

In the drawings:

Figure 1 is a perspective view illustrating 25 the device set up as a single bed or couch,

Fig. 2 is a top plan view with the back or auxiliary frame folded over the top frame,

Fig. 3 is an end view showing the device set up as a double bed,

30 Fig. 4 is a detail horizontal sectional view approximately on the line 4—4 of Fig. 3,

Fig. 5 is an end view of the device in the position illustrated in Fig. 2, and

Fig. 6 is a detail view showing the hook 35 engaging in the opening in one of the ears to hold the members 9 and 26 in one position, the ear being in section.

In carrying out my invention I construct a main body or frame portion of a substantially 40 rectangular formation which includes vertically disposed corner posts 1 arranged two at each of the ends of the body or frame. The corner posts 1 preferably are constructed of angle irons and each pair at 45 the opposite ends of the body or frame are connected with upper and lower transverse members 2 and 3 respectively, the upper connecting members 2 being also formed of angle irons and having their horizontal 50 flanges extending inwardly to the ends of the device, while the lower members 3 may be in the nature of flat bars, and the said bars are more effectively secured to the corner posts by angle braces 4. The corner 55 posts, adjacent their lower ends are also connected by longitudinally extending strips or

bars 5, and these bars are likewise braced by angular members 6 which are secured to the said bars 5 as well as to the respective corner posts 1. The upper connecting members 2 for the posts project a suitable distance beyond the outer corner posts, and the horizontal flanges of the same are provided with spaced perforations to receive the end convolutions of suitable springs 7 providing 60 the spring bottom for the main portion or body of the device.

The lower transverse connecting bars 3 adjacent the outer corner posts of the device have alining openings through which passes 70 a longitudinally extending member in the nature of a rod 8, and this rod has its ends bent angularly, as at 9, and the lower connecting members 3 are provided with outwardly extending flanged portions or lugs 75 10 which are adapted to receive and provide a rest for the said angular ends 9, when the device is set up as a double bed, as clearly illustrated in the drawings.

The ends of the upper connecting members 2 and 3 may be provided with suitable longitudinal connecting elements, but in practice, I have found that by regulating the tension of the spring bottom the same provides an effective seat for the device. 80

The vertical flanges of the upper connecting members 2, adjacent the outer corner posts 1 thereof are also provided with angular extending portions or lips 11, and each of said lips is provided with an opening 12. 90 The inner corner posts have secured to the vertical flanges of the said connecting members 2 projecting ears 13 which are adapted to lap against similar ears 14 provided upon the angle end members 15 of the back or auxiliary frame. The spring bottom has its end members arranged in suitable perforations 17 in the inturned flanged portion of the angular member 15, but the free ends of said angle members are connected by a 95 longitudinally extending rod 18. The ears 13 and 14 are pivotally connected, as at 19, and pivotally secured, as at 20, to the outer members of the angle bars 15 are leg sections 22. Each of these legs comprises an 100 angle member and has one of its flanged portions cut angularly below the pivot so as to provide a shoulder 23 against which the inner flanged portions of the members 15 rest when the legs 22 are swung to a vertical position and the device set up as a double bed. The legs 22 are connected by a 105 long 110

itudinal strip or bar 24 and the said bar is reinforced by angular braces 25 which are connected to the legs as well as to the said strip.

- 5 The numeral 26 designates one arm of an angle member, the same being pivotally connected, as at 27, to the outer flanges of the leg members 22, and the outer arm 28 of the said angle member has its end provided with a bifurcated end 29 which receives the free end of the angular portion 9 of the rod 8, a suitable pivot 30 passing through the ears as well as through the said end of the portion 9 of the rods 8.
- 10 15 These pivots 30 are provided with an outer head 31 and with an inner angular portion or hook 32, and the said hooks are adapted to be swung to engage with the openings 12 in the lips 11 of the main body or frame 20 when the frame 16 is swung at a right angle or in a line with the vertically disposed inner legs of the mentioned main frame to sustain the device in set up position as a davenport.
- 25 30 35 A mattress 33 which is centrally foldable is secured to the springs of both the main frame or body and to the auxiliary frame, so that the mattress may be bent or folded upon itself when the frame 16 is swung over the main frame and the device set up as a single bed. In this last instance it will be noted that the angular arms 9 of the rod 8 rest upon the lugs 10, upon which they are also arranged when the device is set up as a double bed as previously set forth.

Having thus described the invention, what I claim is:

1. In a convertible article of furniture, a main frame including corner posts and an auxiliary frame pivotally connected to the main frame and adapted to be swung and retained over the main frame, at an angle with respect to the main frame, or in a line with the main frame, outwardly extending ears upon the sides adjacent the top and bottom of the main frame, swinging legs upon the auxiliary frame, each of said legs having an offset flange to engage with the auxiliary frame when the same is sustained at a right angle to the main frame, an angular member pivoted to each of the legs, an angular rod pivotally connected to each of the sides of the main frame, a rotatable hook member comprising a pivot and connecting each of the rods with each of the angular

members, said rods adapted to rest upon the lower ears of the main frame when the auxiliary frame is swung over or in a line with respect to the main frame, and the hook 60 pivot members adapted to engage with the upper ears of the main frame to sustain the offset flanged portions of the legs into contact with the auxiliary frame, and to hold the said auxiliary frame at a right 65 angle to the main frame when the same is brought to such position.

2. In a convertible article of furniture, a main frame including angular corner posts, upper and lower transverse members 70 connecting the posts, longitudinal members connecting the posts, angular braces for the connecting members, a rod passing through the lower connecting members, said rod having its ends arranged angularly, an offset 75 member upon the lower connecting members serving as a rest for the angular ends of the rod when in one position, the upper connecting members for the corner posts having an outturned ear provided with an 80 orifice, the inner corner posts having vertical extensions, an auxiliary frame having extensions lapping the said extensions of the main frame and pivotally secured thereto, the said auxiliary frame having its end members 85 formed of angle irons, legs pivoted to the said ends, said legs being also formed of angle irons and having one of their portions cut to provide a shoulder to support the ends of the auxiliary frame when the same 90 is swung horizontally of the main frame, longitudinal connecting members for the legs, an angle member upon each of the legs and having one of its ends pivoted to each of the said legs, the opposite end of the angle 95 member being provided with ears receiving the ends of the angular portions of the rod, a pivot member passing through the ears and through the said ends of the rods, said pivot including a head upon one of its ends 100 and a hook upon its opposite end, and the said hook adapted to swing to engage with openings in the ears of the main frame when the auxiliary frame is moved to a vertical position with relation to the said main 105 frame.

In testimony whereof I affix my signature in presence of two witnesses.

VINCENZO MASSACESE.
